Patented May 23, 1911.

2 SHEETS—SHEET 2.

UNITED STATES PATENT OFFICE.

KARL WACHTER, OF WEINGARTEN, GERMANY, ASSIGNOR TO MASCHINENFABRIK WEINGARTEN, OF WEINGARTEN, GERMANY.

METAL-SHEARING MACHINE.

993,284.

Specification of Letters Patent. Patented May 23, 1911.

Application filed October 19, 1910. Serial No. 587,945.

To all whom it may concern:

Be it known that I, KARL WACHTER, a subject of the King of Würtemberg, residing at Weingarten, Kingdom of Würtemberg, German Empire, have invented certain new and useful Improvements in Metal-Shearing Machines, of which the following is a specification.

This invention relates to certain new and useful improvements in metal shears.

The invention has for its object the provision of simple and improved means for supporting angle irons and T-irons in position to be operated upon by the shears.

15 A further object is to provide means for adjusting the support to permit right or left bevel cuts at an angle less than 45°.

The invention will be hereinafter fully set forth and particularly pointed out in the 20 claims.

In the accompanying drawings:—Figure 1 is a front view of figured iron shears embodying my improvements, the parts being adjusted for a rectangular cutting of figured 25 iron. Fig. 2 is a detail illustrating the parts in position for a left bevel or miter cut. Fig. 3 is a section through Fig. 2 on the line 3—3. Fig. 4 shows a back-view of the figured iron shears with the angle-iron put in 30 for a left miter cut, the support being in the rear. Fig. 5 is a front view of the shears, the same as Fig. 1, with the angle iron put in 35 for a right miter cut. Fig. 6 is a detail front view illustrating a slightly different form of construction in the same position as Fig. 1. Fig. 7 is an end view of Fig. 6. Fig. 8 shows the support according to Fig. 6, adjusted for a left miter cut. Fig. 9 is an end view of Fig. 8.

40 Referring to the drawings A designates my improved metal shears as an entirety the same comprising a base B and a rotary cutting member B'. Secured to one side of the shears A is an adjustable member a provided with a laterally extended tongue b on which is slidably mounted a carrier c provided with beveled ends. Said carrier is locked in its adjusted positions by means of a plug-bolt d carried thereby and adapted 45 to engage any one of the recesses e f or g in tongue b. As illustrated in Figs. 1 to 5 the opening in the carrier c for tongue b is nearer one end of the said carrier than the other, whereby said carrier serves as an

abutment member and is provided with a 55 long projection c' and a short projection c'', either of which may be placed in operative position by simply reversing said abutment member.

An opening D is provided in the shears to 60 receive the metal h to be cut, said metal being supported by the edges of said carrier or opening and said abutment member c.

In the position shown in Fig. 1 the abutment member c is in its medium-position, 65 and the plug bolt d has entered the middle hole e of the guide rail b. The longer end c' of the tongue is pointing upward. In this position the tongue serves only as a down holder and an abutment or support for 70 the rectangular cutting of angle and T-irons. If now the abutment member c is reversed so that its shorter end points upward, and then adjusted to the position where plug bolt d engages the left hole f of the guide- 75 rail b, it cooperates with opening D to support metal h in position to provide a bevel cut at an angle of less than 45° on the left side. The shears can likewise be used after locking the abutment member C at the right 80 hole g of the guide-rail b for beveling angle-irons on the right side at an angle of less than 45°. Each of the projections c' c'' has beveled side and front faces, whereby the 85 abutment is produced.

In the form of construction illustrated in Figs 6—9 the abutment member is not moved from the guide rail b, but is here provided with a suitable insert piece k. Said insert piece k is reversible and provided with two 90 parts k', k'' of different lengths either of which can be inserted in the carrier c'. In the adjustment according to Figs. 6 and 7 the shorter end k'' of the piece k is fixed in the carrier c' and the long end k' is at the 95 top, so that the down-holder is exactly in the position shown in Fig. 1 for holding down angle and T-irons when they are cut rectangularly. If now the tongue c is shifted and the piece k reversed (Fig. 8) this 100 adjustment serves exactly the same purpose as Fig. 2, namely as an abutment for cutting angle-irons under an angle of 45°.

I claim as my invention:

1. The combination with metal cutting 105 shears, of an adjustable member provided with a lateral tongue, a reversible abutment member, and means for adjustably support-

ing said abutment member on said tongue, said abutment member being provided with abutments of different lengths.

2. The combination with metal cutting

5 shears, of an adjustable member provided with a lateral tongue, a reversible abutment member, and means for adjustably supporting said abutment member on said tongue, said abutment member being provided with
10 abutments of different lengths, said abutments being each provided with beveled side and front faces.

3. The combination with metal cutting shears, of an adjustable member provided

15 with a lateral tongue, a reversible abutment member, and means for adjustably supporting said abutment member on said tongue,

said abutment member being provided with abutments of different lengths, and means for locking said abutment member in any ad- 20 justed position.

4. The combination with metal cutting shears, of an adjustable member provided with a lateral tongue, a carrier adjustably mounted on said tongue, and a reversible 25 abutment member removably secured in said carrier and having abutments of different lengths.

In testimony whereof, I affix my signature in the presence of two witnesses.

KARL WACHTER.
